(57) **CLAIM**

I claim the ornamental design for a straw cup, as shown and described.

DESCRIPTION

FIG. 1 is a front, top, and right side perspective view of a straw cup;

FIG. 2 is a front side view thereof;

FIG. 3 is a right side view thereof;

FIG. 4 is a rear side view thereof;

FIG. 5 is a left side view thereof;

FIG. 6 is a top view thereof; and,

FIG. 7 is a bottom view thereof.

The broken lines in FIGS. 1–6 depict a straw that forms no part of the claimed design. The broken lines in FIG. 7 depict portions of the bottom that forms no part of the claimed design.

1 Claim, 6 Drawing Sheets(56)
